FORM ISSUING MACHINE

Elmer G. Streckfuss, Cincinnati, Ohio, assignor
to The Cincinnati Time Recorder Company,
Cincinnati, Ohio, a corporation of Ohio

Application September 8, 1939, Serial No. 293,997

3 Claims. (Cl. 164—42)

My invention relates to certain improvements in form issuing machines, which I have applied specifically to a certain machine forming the basis of my application for Letters Patent Serial No. 219,000, filed July 13, 1938, in which a machine particularly adapted to issuing of insurance forms upon deposit of a coin for the price thereof, is provided for. In such a machine the arrangement is such that the policies or other forms require the signature of the applicant on an original and a duplicate, but this signature must be placed on a form which is imprinted with the date and hour at which it is issued. Thus in that machine the policies were delivered by the machine in plural copies with suitable transfer coating on the back of the outer form over a writing table. However the opening through which the policies were available for signature and entering of required data, was controlled by a window which was not released until a coin was deposited. At the instant of opening this window, a printing device which was time controlled, printed the date on the particular form on which entries were to be made. Thereafter the topmost form was fed out of the machine, and the underneath one stored therein, for company record.

The said machine was equipped preferably with a pin wheel feed device, not of my invention, and this feed device could not be operated and was locked against operation, until a separate push button was depressed whereupon one form length of material only was fed from the machine, which machine was then locked again.

It was found that this machine which required the tearing off of the issued form from a continuous sheet held otherwise within the machine sometimes led to difficulty, owing to the fact that the tearing off would be ineffectively done, resulting in defacing the policy or the ensuing form and clogging up the machine upon the next operation. It is to the end of providing a cut-off device for positively severing the issued form from the retained strip that my present invention is directed.

It is my object to provide for an effective, easily timed rocking cut-off knife operating in synchronism with the feed-out mechanism.

More particularly I employ the power used for effecting other operations in the machine to place the knife under spring tension. Then at the conclusion of the feeding operation this tension is released and the spring operates the knife.

I am further enabled, having this cut-off knife, to avoid the necessity of ever clamping the pa-

per within the machine, as by a plate covering the paper webs and holding them down on the pins, but controlled by a cam to clamp against the webs at the end of each feeding operation. Thus one of my improvements is a pair of plates, one a deflector for the retained form, and one a hold down for the issued form which work quite well with the cut-off device to avoid any clogging of the paper at the issue point.

Another advantage which might be noted is that the cut-off point is such that no edge of paper must project where it could be reached by a person endeavoring to tease a policy out of the machine without proper entry. Accordingly, I am able to add additional protection. Thus I have devised a spout which is connected to the issue point from the cut-off knife and extends down through a considerable space, to its delivery mouth. The form falls through this spout by gravity and the force of the issue, and there is no way in which the machine can be tampered with by seizing a projecting edge of paper, which is the case where a form must be torn off from a retained strip.

The above objects and other advantages to be noted, I accomplish by that structure of which an example will be shown in the attached drawings. The novelty inherent in the structure, and which will be applicable to a wide range of machines, will be set forth in the appended claims.

In the drawings:

Figures 1, 2 and 3 are respectively a plan view, side view and front view of a strip dispensing machine embodying my invention.

Fig. 4 is an enlarged side elevation with parts broken away and certain parts in section.

Fig. 5 is a fragmentary view showing an alternate position of certain of the parts seen in Fig. 4.

Fig. 6 is a plan view with parts broken away showing a portion of the strip feeding mechanism and the cut-off knife during the period in which the feeding mechanism is in operation.

Fig. 7 is a section taken along line 7—7 of Fig. 6.

Fig. 8 is a fragmentary section illustrating the position of the cut-off knife after the strip has been severed.

Fig. 9 is a perspective of a bracket employed for supporting the knife.

I have not shown in all of its details the structure of my application for Letters Patent Serial No. 219,000 above referred to, and wish to make reference here to the said application for a complete description. It suffices for my pres-

ent purpose to show the enclosing casing 1, the coin chute 2, the coin switch 3, and the paper support and feed devices generally indicated at 4, omitting the printing mechanism, which is not essentially involved in my present invention. My invention has importance chiefly in form issuing machines with an enclosed casing, where a retained duplicate is kept in the machine, and where it is desirable to avoid the necessity of tearing off the issued form from the strips left in the machine for the next operation. Due to the fact that my present machine is electrically operated, I am enabled to utilize the initial current supplied to the machine upon a solenoid, when a coin is deposited, or a key turned or the like, to raise and place under spring tension the cut-off knife, and thus at the close of the operation when the feed is completed I can, without use of power at the time that current supply is going off and the parts coming to a stop, simply release the current to the solenoid which permits the knife to snap down and perform its function.

In other forms of machines, where it is necessary to move a shutter over the paper support to disclose the form to be written upon by manual force, I could use this manual force to raise and tension the knife, and release it with a latch at the close of the manual feed. It is better to get the knife clear out of the way before the paper feed starts, hence it is best to use some other operation rather than the initiation of the feed to raise the knife. Any operation incident to placing the feed device in condition for operation would suffice so far as the general aspects of my invention are concerned.

Referring to Figs. 4 and 5 when a coin is deposited in the coin slot 5 it passes down through the chute 2 momentarily closing the switch 3 as it passes from the bottom of the chute into the coin receiving box 7. The chute 2 contains means for rejecting spurious coins and any such coins are returned through the opening 8.

Momentary closing of the switch 3 causes the magnet 9 to attract armature 10 which armature is pivoted at 10a and urged to the position seen in Fig. 4 by a tension spring 10b. Movement of the armature closes the contacts 11 and 12 and engages the latch 13 which latch retains the contacts in closed position until said latch is released as will be later described.

The closing of contacts 11 and 12 establish circuits which (by mechanism not here shown) actuate the printing hammer 14 and retract the shutter 15 so that a portion of the strip 16 is exposed for applicants' signature through the opening 17 in the casing 1.

Also actuated by closing of contacts 11 and 12 a solenoid 19 attracts the plunger 20 to move the lever 21 and shaft 22 in clockwise direction against tension of spring 20a, as seen in the drawings. Thus the position of the parts will be as seen in Fig. 5 and the cut-off knife, which is fixed to the shaft 22, will assume the position seen in Fig. 7 where the knife is shown at 23.

As the applicant applies his signature to the strip 16 a carbon coating on the under side thereof of duplicates said signature upon an underlying strip 24 which strip 24 is to be retained in the machine as indicated at 25.

Also controlled by contacts 11 and 12 a branch circuit running to the strip feeding mechanism has a normally open switch 26. The switch 26 is of the push button type and is to be depressed

after applicant has completed his signature and is ready to receive his copy of the policy.

Pressing the switch or button 26 completes the just mentioned circuit and energizes a motor (not shown) which motor, operating through suitable reduction gearing, drives the shaft 27 in a clockwise direction of rotation. Fixed to shaft 27 the pin wheels or sprockets 28 and 29 engage perforations 30 at either side of the strips and push the strip 16 under knife 23 and into the curved delivery chute 31. The strip 24 having the duplicate signature is transferred to the pile 25 and a new section of both strips is withdrawn from the pile 25a.

Fixed to the outer end of shaft 27 an arm 27a is provided with a stud 27b which stud serves to release the latch 13 after shaft 27 has made one complete revolution.

When the latch 13 is released the spring 10b returns the armature 10 to the position of Fig. 4. This breaks the circuit flowing through contacts 11 and 12 and all mechanism within the machine is de-energized. As this occurs the spring 20a turns the shaft 22 and knife 23 in counter-clockwise rotation through an arc of movement sufficient to sever the advanced portion of the strip 16, allowing same to drop freely through the chute 31 where it emerges from the machine through opening 31a in the casing.

As illustrated in the drawings the knife 23 is formed of a rod having a portion thereof milled away so that the knife body is of semi-circular form. The cutting edge 23a of the knife is preferably formed as a slight helix. To obtain shearing action the knife 23 operates against the bar 23b. For supporting the bar 23b and knife 23 in operative relation I employ brackets 32 and 33 one of which is shown in Fig. 9. The brackets have holes 33a for screws 34 by which they are attached to the side frame members 35 and 36 of the machine. Also provided in each bracket the hole 37 provides bearing for the knife shaft 22. An inwardly bent portion 38 with a tapped hole 39 supports the fixed knife member 23b which is retained by screws 23c. Also retained by the screws 23c the small angle brackets 40 provide support for the hold-down plate 41 for strip 16 as will be presently described. Adjustment screws 42 are arranged to bear against the member 23b urging said member toward the knife 23. By forming elongated or oversize screw holes in member 23b an accurate adjustment of the cutting edges may be readily obtained, after which the screws 23c are secured to retain the adjustment.

Referring to Figs. 4, 6, and 7 the paper support plate 50 extends from beneath the opening 17 to the feed mechanism 4 at which point a pair of upturned ears or lugs 51 are provided. These ears engage shoulders 52a of the deflector plate 52 to restrain the plate from being carried along with the paper. Extending downwardly from the shouldered portions 52a the ears 52b retain plate 52 in correct transverse alignment. At its rear end the plate 52 rests on member 23b. As the plate is not fastened in any manner it is readily removable for threading the machine. Cut out portions 52c in the plate permit the sprocket teeth or pins of the drive wheels to engage the strips 16 and 24. The strip 24 need not be severed, and when threaded into the machine is passed below the plate 23b (see Fig. 7).

The hold down plate 41 for the upper strip 16 is pivoted on a rod 41a, which rod has bearing in the brackets 40 already mentioned. Cut-away

portions 41b at each side of the plate eliminate interference with the sprocket teeth and an arch shaped projection 41c has affixed at its outer edge a bent wire 60, said wire being arranged to brush against the outer margin of strip 16 to insure engagement of the strip with the sprocket teeth.

A guide member 61 for directing the strip 16 into chute 31 is shown underlying the knife 23. As shown, this member is fixed to the side frames 35 and 36 by screws 62 and 63.

Referring again to the cut-off structure, it will be observed that the act of setting the machine into condition for operation energizes a solenoid 19, which sets the spring 20a on the knife bar into tensioned position at the same time swinging the knife bar upwardly, ready to cut off the next set of forms to be fed. The operation of the knife bar is caused by the movement of the shaft of the paper feeding device. At a given point in its revolution, just before it comes to rest, this feed shaft trips the latch 13, whereupon the current is broken to the solenoid through opening of the switch 11, 12. The result is that the knife, being under tension of the spring, and raised by the initial action of the solenoid 19, swings through its cutting stroke, when the paper movement has stopped, and cuts off the forms to a length determined by the single rotation of the feeding device.

It will be understood that various modifications of my invention will readily occur and that I am not to be limited to the construction as shown and described.

Having thus described my invention, what I claim as new and desire to secure by Letters Patent:

1. In combination with a form feeding device a cut-off structure comprising a knife arranged to cut off a form, means operated by other than the form feeding device for placing said knife under tension, and means controlled by the form feeding device for releasing the said knife at the close of a form feeding operation so as to permit its movement due to said tension thereby cutting off a form, said form feeding device including an enabling element and means for requiring operation of the knife tensioning means incident to operation of the enabling element.

2. In combination with a rotary form feeding device arranged for single revolution operation to feed one form length of a continuous form per revolution, an enabling element operated by other than the form feeding device requiring operation previous to each single revolution of said feeding device, a cut-off knife, means for placing said knife under tension incident to operation of the enabling element, and means operated by the feeding device at the end of a feeding revolution to release the knife, whereby it moves under said tension to cut off a form length which has been fed.

3. In combination with a form feeding device a cut-off structure comprising a knife arranged to cut off a form, means operated by other than the form feeding device for placing said knife

under tension, and means controlled by the form feeding device for releasing the said knife at the close of a form feeding operation so as to permit its movement due to said tension thereby cutting off a form, said means for placing the knife under tension comprising a solenoid.

4. In combination with a form feeding device a cut-off structure comprising a knife arranged to cut off a form, means operated by other than the form feeding device for placing said knife under tension, and means controlled by the form feeding device for releasing the said knife at the close of a form feeding operation so as to permit its movement due to said tension thereby cutting off a form, said means for placing the knife under tension comprising a solenoid, an electric circuit requiring to be closed previous to a feeding operation of the feeding device, and means requiring energization of the said solenoid incident to closing the said electric circuit.

5. In combination with a form feeding device, a movable cut-off knife, means operated by other than the form feeding device for retracting said knife against spring tension, and means controlled by the form feeding device for releasing the knife from its retracted position at the close of a form feeding operation, the said knife arranged to cut off a form when released, said means for retracting the knife comprising a solenoid, an electric circuit requiring to be closed previous to a feeding operation of the feeding device, and means requiring energization of the said solenoid incident to closing the said electric circuit.

6. In combination with a form feeding device means requiring closing of an electric circuit incident to each feeding operation thereof, a cut-off device arranged to sever forms fed by the feeding device, said device comprising a solenoid in said circuit to retract the knife upon closing of said circuit, a movable knife, and a spring opposing its retraction, and means whereby the feeding device opens the said electric circuit at the close of each feeding operation.

7. A cut-off device comprising a rocking knife, a bar against which the rocking knife cuts and over which a strip to be cut off is fed, a solenoid, connections from the solenoid to rock the knife, and a spring opposing said rocking movement, whereby it is necessary only to open the circuit of the solenoid to cause the knife to perform a cutting operation due to the action of the spring.

8. In combination with a rotary pin feed for marginally apertured forms, in plural copies, a cutter bar, a cut-off knife cooperating therewith, a gravity plate resting on the cutter bar and lying over the undermost form, a second gravity plate resting on the uppermost form, said plates being cut so as to leave the feed pins exposed, and means on the upper plate to engage the topmost form along its margin outside of the apertures.

ELMER G. STRECKFUSS.
